JOHN ATWOOD, JR., AND THOMAS M. HATCH, OF PROVINCETOWN,
MASSACHUSETTS.

Letters Patent No. 86,490, dated February 2, 1869.

IMPROVEMENT IN BOAT-DETACHING APPARATUS.

The Schedule referred to in these Letters Patent and making part of the same.

Be it known that we, JOHN ATWOOD, JR., and THOMAS M. HATCH, both of Provincetown, in the county of Barnstable, and State of Massachusetts, have invented a new and improved Self-Detaching Davit, or Boat-Tackle, of which the following is a full, clear, and exact description, reference being had to the accompanying drawings, making a part of this specification, in which—

Figure 1 is a side elevation of a tackle-block embodying our invention.

Figure 2 is a transverse vertical elevation in a plane parallel to the axis of the pulleys or sheaves; and

Figure 3 is a side elevation of a block, one cheek having been removed, showing the interior mechanism of one arrangement of our invention.

The object of our invention is to furnish a ready and efficient means of instantly detaching a boat, when lowered from the davits of a vessel of any description, whether at rest or in motion, in a smooth or rough sea, the instant such boat touches the water, or floats.

Further, our general purpose is to furnish a tackle-block, which will release itself when at a point inaccessible to workmen, or which, by releasing itself after the safe deposition of the load attached, of what nature soever, will economize time.

The invention consists in such a combination of the hook and block, that, after the withdrawal of a retaining bolt, or pin, the hook of the block is instantly, when the strain upon the block is relieved, thrown from its usual position, setting free the rope or pin attached to it.

Our invention may be applied to any tackle attached to a mass, which it is desired to deposit in an inaccessible position, or at the bottom of a river or harbor.

Time would be much economized by its employment as a part of the tackle of all lifts and derricks, for the immediate detachment of the load from the derrick, or lift, when it is laid in the proper place, would greatly increase the efficiency of such derrick, enabling it to perform much more work in a given time.

Our invention is especially applicable for the releasing of ships' boats from the davits under all circumstances. Nautical exigencies demand that no time shall be lost, and the swamping and staving in of boats, resulting from their detachment not having been effected at the right moment, is often attended with loss of life.

Referring to the drawings—

a is the frame, or shell of the block. It contains two chambers, in which the sheaves *e e* turn freely about a pin, *f*, which passes entirely through the block transversely, and is secured at the ends, as in the block at present employed. A ring, for attaching the block to the rope, is fixed to its upper end.

A narrow, deep, vertical slot or chamber penetrates

the middle of the block, from its front almost to the back, as shown in fig. 3. This chamber allows the hook *c* to be turned about its axis *f*.

The hook *c* has a long straight shank, through the upper part of which the axis *f* passes. This hook *c* is so shaped that, when turned about the axis *f*, a rope or ring would be detached freely, and without hitching, from the hook.

With the hook *c*, a spring of metal, or other elastic material, is so combined that, when the shank of the hook *c* is in a vertical position, the spring is compressed or extended.

The spring may be attached to the block *a*, or hook *c*, in any suitable manner.

A bolt, *g*, passes transversely across the foot of the block, and in front of the hook *c*, thus retaining it in its usual position, in spite of the tendency of the spring to throw it out and up.

The bolt *g* passes through bearings, and is attached in the usual manner.

After the withdrawal of the bolt *g*, which may be done at pleasure, the hook *c*, the instant the load slackens, or when the boat touches the water, or a load the ground, is thrown, by the spring, out of its place, and the block is free.

In the accompanying drawings, the spring *d* represents an elastic rubber cord, or strap, one end being attached to the hook *c*, and the other to the upper part of the chamber, in any suitable manner.

The hook *c* can readily be returned to its usual place, the bolt *g* reinserted, and the block again be ready for use.

The tackle-block, constructed as above described, is in no respect necessarily weaker than those of the ordinary construction.

The detachment of the hook of blocks now in use requires often considerable time and the expenditure of a good deal of strength.

In certain cases the bolt *g* may be dispensed with altogether, but it is well to retain it, so that the block may be employed when self-detachment is not desired.

What we claim as our invention, and desire to secure by Letters Patent, is—

1. The movable hook *c*, in combination with the block, constructed and operated as described.

2. The block *a*, in combination with the hook *c* and a spring, substantially as and for the purpose set forth.

In testimony whereof, we have signed our names to this specification, in the presence of two subscribing witnesses.

JOHN ATWOOD, JR.
THOMAS M. HATCH.
